UNITED STATES PATENT OFFICE.

ALFRED W. FRENCH, OF PIQUA, OHIO.

APPARATUS FOR PACKING OIL-CAKES.

SPECIFICATION forming part of Letters Patent No. 723,455, dated March 24, 1903.

Application filed October 7, 1901. Serial No. 77,755. (No model.)

To all whom it may concern:

Be it known that I, ALFRED W. FRENCH, a citizen of the United States, residing at Piqua, in the county of Miami and State of Ohio, have ⁵ invented new and useful Improvements in Apparatus for Packing Oil-Cakes, of which the following is a specification.

This invention relates more particularly to a machine for packing oil-cakes into bags; ¹⁰ but it is also applicable to other uses where it is desired to pack a quantity of thin flat cakes or other articles of an analogous shape into bags.

Oil-cakes are usually packed in the bag in ¹⁵ the form of a pile—that is, one on top of the other—with one or more cakes inserted edgewise at each side of the pile between the side edges of the piled cakes and the adjacent side of the bag, which edgewise cakes assist ²⁰ in tightly filling the bag and add to the neat appearance and compactness of the completed package.

The object of the present invention is to provide a machine of simple and inexpensive ²⁵ construction which will quickly and with little labor on the part of the operator pack the bags in this manner by introducing the pile of cakes so arranged directly and as a whole into the bag.

³⁰ Other objects will appear from the following description.

In the accompanying drawings, consisting of three sheets, Figure 1 is a side elevation, partly broken away, of a machine illustrating ³⁵ my invention. Fig. 2 is a plan view thereof, partly broken away. Fig. 3 is an end elevation of the cake-support, showing a pile of cakes thereon. Fig. 4 is an end view of a filled bag of cakes. Fig. 5 is a transverse section ⁴⁰ through the pusher-operating cylinder and associated parts on the line 5 5, Fig. 2. Fig. 6 is a transverse section through the bag-holder on the line 6 6, Fig. 2. Fig. 7 is a detail section of the three-way valve controlling ⁴⁵ the pusher-cylinder.

Like letters of reference refer to like parts in the several figures.

Referring to the drawings, A indicates a support or table for a pile of cakes, at one ⁵⁰ side of which is arranged a bag-holder, and at the opposite side of which is arranged a horizontal hydraulic cylinder C, supported in

any suitable manner, as by means of brackets or standards c.

D is a fluid - operated piston or plunger ⁵⁵ which is arranged and adapted to reciprocate in the cylinder C and carries at its forward end a pusher or head D', which travels back and forth over the support or table A.

In the drawings I have shown the packing- ⁶⁰ machine associated with an oil-cake-trimming machine and adapted to receive and pile the cakes directly from the latter, so as to avoid the handling of the cakes. For this purpose the support or table for the piled cakes is of ⁶⁵ the type of receiving and piling table shown and described in my application for United States Letters Patent filed November 30, 1900, and serially numbered 38,127.

E indicates a portion of the trimming-machine, in which the cakes are carried by an endless carrier e past the trimming-knives, (not shown,) which remove the soft edge portions of the cake, and then discharged successively onto the support or table A. The ⁷⁰ latter is automatically lowered intermittently as the cakes are fed thereto to retain the top of the pile of cakes at the proper relative height by suitable mechanism—such, for instance, as described in said application and ⁷⁵ which is as follows:

The support is carried by an upright plunger or piston F, working in a hydraulic cylinder f, which is provided with a pipe f' for supplying fluid under pressure thereto, and ⁸⁰ an escape-pipe f², connecting with the supply-pipe.

f³ is a valve controlling the supply-pipe, and f⁴ is a valve controlling the escape-pipe. An arm f⁵, arranged above the support or ⁸⁵ table A and in the path of the cakes as they leave the trimming-machine, is connected to a rock-shaft f⁶, which is connected by a second arm f⁷ and a rod or link f⁸ with an arm on the escape-valve f⁴. Each cake as it passes ⁹⁰ the arm f⁵ raises the same and through the said connections opens the escape - valve, which permits the plunger and support or table carried thereby to descend until the arm f⁵, which rests on the uppermost cake of ⁹⁵ the pile, lowers sufficiently to close the escape-valve. The connections are adjusted so that the support or table lowers a distance equal to the thickness of a cake at each open-

ing of the valve, and the operation is repeated for each successive cake. When sufficient cakes have been thus piled on the support to approximately fill a bag, which is indicated 5 in any suitable manner—for instance, by a gage-rod G, secured to one side of the support or table—the escape-valve f^4 is opened by hand and the plunger and support are allowed to descend until a collar g on the plunger contacts with a suitable stop, such as the top of the cylinder f, in which position of the parts the top face of the support or table is on the horizontal plane of the bottom of the bag-holder and somewhat below the lower edge of 15 the pusher D'.

f^9 indicates wide spring-plates arranged vertically at the sides of the support or table A. They are bowed inwardly and center the cakes on the support or table and guide the 20 pile when it is pushed from the support or table into the bag.

f^{10} indicates longitudinal raised ledges or ribs at the sides of the support or table on which the side cakes rest for the purpose of 25 raising the lower edges of the side cakes above the top face of the support to prevent their catching on the lower side of the bag when the pile is moved into the same. The support or table may, if preferred, be any suitable 30 stationary support, and the cakes may be piled thereon by hand.

The means shown in the drawings for operating the pusher-plunger D is as follows:

H indicates a pipe connecting with a branch 35 pipe H' for supplying liquid under pressure to the cylinder C, and H² an escape-pipe connected therewith at the juncture of the pipes H and H'. Both the supply and escape pipes are preferably controlled by a three-way 40 valve or turn plug h, located at the juncture of the pipes. This valve is provided with an operating-arm h', connected, as by a chain h², to one arm of a substantially horizontal lever h³, pivoted to a suitable support, preferably 45 below the cylinder C and below the floor or supporting-surface of the machine. The outer or forward end of the plunger or the pusher is connected to the forward end of a chain or the like I, which passes over a pulley or sheave i, journaled on any suitable support, such as one of the cylinder-standards, and carrying at its other or lower end a weight or weights i'. The chain I passes through a 50 loop or eye i² on the other arm of the lever h³ and has secured thereto below the lever an adjustable stop or trip device i³. When it is desired to push the pile of cakes from the support or table into the bag which has been placed on the bag-holder, the valve-arm h' is 55 turned upwardly to connect pipe H with the branch pipe H' or open the supply-pipe, and this movement tilts the lever h³ to throw the loop end thereof down. The fluid entering the cylinder forces the plunger forward or 60 outward to the desired limit of its movement, when the stop or trip device i³ engages the loop i² and returns the lever to its normal

position and through its connection with the valve h closes the same, cuts off the liquid-supply, and stops the outward movement 70 of the plunger. When it is desired to return the plunger and pusher, the plug h is turned to connect the escape-pipe with the branch supply-pipe H' and permit the escape of the liquid from the cylinder. The weights i' then 75 move the plunger inward.

J indicates a horizontal guide arranged between the forward end of the cylinder C and the rear end of the cake support or table at the height of the upper face of the latter. 80 The pusher is preferably provided at opposite sides of its lower edge with casters or rollers j, adapted to roll on said guide and the cake support or table for preventing the sagging of the plunger and guiding the pusher. 85 The pusher is preferably provided with a front metallic face-plate j', which projects at its top slightly above the top of the pusher.

K indicates a removable or detachable upper section for the pusher, to which latter it 90 is attached by means of hooks or the like k on the back of the detachable section engaging over the upper projecting edge of the face-plate j' of the pusher. The detachable section K is preferably formed of sheet metal and has 95 its opposite ends turned forward to provide vertical end flanges K' for engaging the side cakes, as will be hereinafter explained.

The bag-holder is preferably constructed as 100 follows:

L indicates parallel horizontal supporting timbers or pieces placed in the rear of the cake support or table. The bottom, top, and side holding plates or pieces for the bag are indicated, respectively, at M, M', M², and M³ 105 and are preferably arranged as shown in the drawings. The bottom plate is supported at its opposite sides on the supporting-timbers L and is inclined or beveled downwardly at its front end, which is pivoted to the upper 110 front corners of the timbers L in any suitable manner, as by means of a transverse rod m, secured to the under side of the inclined front portion of the plate, and the ends of which enter sockets in the timbers. The bottom plate is thus supported substantially on the level of the upper face of the cake support or table, and the front end is slightly below this level, so that the lowermost cake of 115 the pile will be guided thereby and slide 120 easily on the bottom plate. The side plates M² and M³ are arranged vertically at the opposite sides of the bottom plate and above the same. The front ends of the side plates are preferably inclined or flared outwardly, 125 so as to guide the cakes into the holder. The side plates are secured in any suitable manner to upright posts N, arranged opposite each other, one outside of each piece L. The lower portion of each post N extends down 130 through horizontally-elongated slots n in upper and lower brackets n' n², secured to the adjacent timber L. The slots in the brackets permit the posts to move bodily toward and

away from each other. Each post is provided with an upper and lower loose collar o and o' , the upper collars o of the opposite posts being connected by an upper transverse spring O and the lower collars o' being connected by a second transverse spring O' . The springs pass through registering holes o^2 in the timbers L and the backs of the brackets $n' n^2$ and act to hold the posts yieldingly in their innermost positions or against the inner ends of the slots n . (See Fig. 6.) The collars being loose on the posts permit the same to be turned or moved up and down in their brackets without moving the collars. The side plates are held in their normal position, (shown in Fig. 2,)—that is, substantially parallel—by a transverse spring p , the ends of which are connected to the front ends of arms P , one secured to each post N and projecting forwardly beside the adjacent timbers L . The spring holds the arms P against the outer faces of the timbers L , which thus constitute stops for the arms. The rear ends of the side plates are adapted to be swung in or toward each other for the purpose of placing the bag over the holder. Each post N is provided at or near its upper end with a rearwardly-projecting arm p' , which arms are pressed toward each other to throw the rear ends of the side plates inward.

p^2 indicates a chain or the like connected to one arm and provided with a ring or loop p^3 at its free end, which is adapted to be slipped over the end of the other arm to hold the arms and plates in their inner position.

The top plate M' is preferably detachably hung, as by means of hooks q , on a transverse rod Q , which is loosely supported above the top edges of the side plates by links q' , pivoted at their upper ends, one to each post N . The top plate preferably tapers slightly toward its rear end to enable it to be more readily slipped into the bag and has its upper forward end bent or inclined upwardly, so as to guide the cakes into the holder. The top plate normally occupies the inclined position indicated in Fig. 1, and as the cakes are pushed into the bag the top of the pile engages the top plate and moves it up until it is substantially parallel with the bottom plate. The plates of the holder are preferably made of sheet metal and, as will be observed, constitute, in effect, an expandible rectangular box or lining for the bag. The cakes in being introduced into the bag therefore cannot engage with the sides thereof and disengage the same from the holder.

In order to enable the bag to be more easily placed on and removed from the holder, provision is made for raising the rear end of the bottom plate and the side plates up sufficiently to enable the lower side of the bag to be readily slipped under the same. The means shown in the drawings for accomplishing this is as follows:

R indicates a treadle-lever secured intermediate of its ends to one end of a transverse

rock-shaft r , journaled in suitable bearings or openings in the timbers L , beneath the bottom plate of the bag-holder. The rear end of the lever engages beneath a fixed collar r' on the adjacent upright post N . At the opposite end of the rock-shaft r is secured an arm r^2 , the rear end of which engages beneath a similar fixed collar r^3 on the other post N . It will thus be seen that by depressing the forward end of the treadle-lever the rear end thereof and the arm r^2 move up and lift the posts and side plates.

S indicates an arm secured to the rock-shaft r between the timbers L and having an upwardly-extending rear end, which engages the bottom plate M in rear of its pivot and tilts the rear end thereof up when the treadle is depressed.

In the use of the machine the cakes are piled automatically on the support or table A , as above described, directly from the trimming-machine and the table lowered to the position indicated, or they may be placed by hand on a stationary support or table. A cake is preferably placed vertically or on edge at each side of the pile, between the same and the side retaining-springs f^9 and resting on the raised side ledges f^{10} of the support or table. The top plate M' of the bag-holder is then detached from its supporting-rod and removed from between the side plates $M^2 M^3$, the rear ends of which are then swung toward each other by means of the arms p' and are held in this inner position by engaging the ring at the end of the chain p^2 , which is attached to one arm over the opposite arm. The treadle R is then depressed, which, as before explained, raises the bottom and side plates, and a bag is slipped over the holding-plates, preferably with its mouth or open end turned or folded back, as indicated in Fig. 1. The treadle R is then released and the chain-ring p^3 disengaged from the arm p' , and the spring p draws the arms P toward each other until they are stopped by the timbers L , in which position the side plates stand substantially parallel and distend the bag. The top plate M' is then replaced on its supporting-rod in the inclined position indicated in Fig. 1 and the bag is ready to be filled. The turn-plug h is then turned by means of its arm h' to admit the fluid to the cylinder C and cause the plunger to move out and carry the pusher across the support or table A , which pushes the cakes into the bag-holder. The length of movement of the plunger is sufficient to cause the forward end of the pile of cakes to engage the bottom of the bag and push the same off of the bag-holder. The outward movement of the plunger is stopped by the trip device and connections, as already explained. When it is desired to return the plunger, the plug is turned so as to connect the escape-pipe with the branch supply-pipe and permit the escape of fluid from the cylinder C . The cakes vary somewhat in size, so that the pile may be somewhat larger in height or breadth than the

cross dimensions of the bag. The side plates having flaring or outturned ends can receive the pile, and as the latter is forced into the bag-holder it forces the side plates bodily 5 apart, which stretch or expand the bag. This bodily lateral movement of the side plates is permitted by reason of the described manner of mounting the upright posts, to which the plates are secured. The top plate being piv- 10 oted is free to rise as the pile is shoved into the holder, and if the pile is somewhat higher than the upper side of the bag the links permit the top plate to rise bodily without bending and raise or stretch the upper side of the 15 bag for its full length. The removable upper section of the pusher insures the positive engagement of the pusher with the uppermost cakes and insures their movement with the pile. Before the plunger has reached the end 20 of the stroke the detachable section is removed, so that the same will not contact with the bag-holder. The upright side flanges k' of the detachable section engage the rear ends 25 of the vertical side cakes and prevent their disengagement from the pusher.

I claim as my invention—

1. The combination of a bag-holder, a pusher movable toward and from said bag-holder, a vertically-movable support for the 30 cakes arranged between said bag-holder and said pusher, and means for holding the said cake-support in a position such that the cakes thereon are directly opposite to said bag-holder, substantially as set forth.
- 35 2. The combination of a bag-holder, a pusher movable toward and from said bag-holder, a vertically-movable support for the cakes arranged between said bag-holder and said pusher, means for intermittently lowering said support, and means for holding said cake-support in a position such that the cakes thereon are directly opposite to the bag-holder, substantially as set forth.
- 40 3. The combination with a support for the cakes, of means for holding a bag, a pusher for moving said cakes from said support into the bag, a supplemental pusher-section, and means for supporting said supplemental section on the pusher in position to increase the 45 size of the latter, substantially as set forth.

4. The combination with a support for the cakes, of means for holding a bag, a pusher for moving said cakes from said support into the bag, a pusher-section detachably secured to said pusher, and means for operating said 55 pusher, substantially as set forth.

5. The combination with a support for the cakes, of a bag-holder, a pusher for moving the cakes from said support into a bag on the bag-holder, fluid-operated mechanism for actuating said pusher, a valve controlling the fluid for said fluid-operated mechanism, and means operated by a movable part of said mechanism for actuating said valve, substantially as set forth. 60

6. The combination with a support for the cakes, of means for holding a bag, a pusher for moving the cakes from said support into a bag on the bag-holder, a fluid-operated means for operating said pusher, a valve controlling the fluid to said means, and a device 65 operated by said pusher for actuating said valve, substantially as set forth. 70

7. The combination with a support for the cakes, of means for holding a bag, a pusher, 75 a plunger which carries said pusher, a cylinder in which said plunger reciprocates, a valve controlling the supply of fluid to said cylinder, a trip device connected with said plunger, and means actuated by said trip device 80 for actuating said valve, substantially as set forth.

8. The combination of a support for the cakes, of means for holding a bag, springs arranged at the sides of said support for guiding the cakes, and means for moving the cakes from said support into the bag, substantially as set forth. 85

9. The combination with a support for the cakes, of means for holding a bag, means for 90 moving the cakes from said support into the bag, raised ledges at the sides of said support, and guides at the sides of said support, substantially as set forth.

Witness my hand this 23d day of September, 1901.
